UNITED STATES PATENT OFFICE.

ALFRED W. F. GUEST, OF BROOKLYN, NEW YORK, ASSIGNOR TO MERGENTHALER LINOTYPE COMPANY, A CORPORATION OF NEW YORK.

LINE-CASTING MACHINE.

Application filed March 22, 1928. Serial No. 263,611.

This invention relates to line casting machines of the general organization represented in U. S. Letters Patent to O. Mergenthaler, No. 436,532, wherein circulating matrices are selected and assembled in line together with expanding spaces, and the line thereafter presented to the front of a slotted mold, expanded or justified between a pair of confining jaws, and finally, after the casting operation, elevated from the jaws and distributed.

In practice it is necessary to change frequently the length of the slugs or linotypes produced, according to the width or measure of the page or column to be printed. Consequently, the mold slot in which the slugs are cast is made variable in length, and one of the confining jaws is also made adjustable to correspond, so that lines of one length or another may be used at will. The means usually employed for adjusting the movable left hand jaw (the opposing jaw being relatively fixed) has embodied parts which may protrude from one to five inches beyond the left end of the vise frame and are thus not only in themselves exposed to damage but seriously obstruct the passage between and around machines. It is the object of the present invention to obviate these difficulties and at the same time enable the operator while seated at the keyboard to adjust the jaw, with the same facility as heretofore, instantly and accurately to any required measure. To this end, the movable jaw is connected to a rotatable screw which is confined between the ends of the vise frame and adapted by its rotation to effect the adjustment of the jaw for the matrix lines of various lengths, means (which include a device for indicating in ems and fractions thereof the different adjusted positions of said jaw) being provided for rotating the screw and for locking it against rotation to locate the jaw in any selected position.

In the accompanying drawings, the invention has been shown merely in preferred form and by way of example but obviously many changes and variations may be made therein and in its mode of application which will still be comprised within its spirit. It should therefore be understood that the invention is not limited to any specific form or embodiment except in so far as such limitations are specified in the claims.

Referring to the drawings:

Fig. 1 is a front elevation showing the application of the present improvements, the vise frame being indicated in broken lines;

Fig. 2 is a top plan view of the parts shown in Fig. 1;

Fig. 3 is an enlarged cross section taken on the line 3—3 of Fig. 1;

Fig. 4 is an enlarged face view of the crank disk, and parts associated therewith, employed for operating the jaw adjusting screw;

Fig. 5 is a horizontal section taken on the line 5—5 of Fig. 4; and

Fig. 6 is a face view of a crank disk of alternative form.

A composed line of matrices and spacers when presented at the casting level is confined endwise between a pair of vise jaws, A, B which are carried respectively by angular blocks A¹, B¹ mounted in a stationary portion C of the main frame, the latter being commonly known as the "vise frame". The block A¹ is formed with bearing portions A², A³ slidably mounted in suitable guideways C¹ (Fig. 3) so that the left-hand jaw A may be moved horizontally toward and from the fixed opposing right-hand jaw B to vary the distance therebetween according to the length of the matrix lines employed. In order that justification of the lines may take place properly, it is necessary that the jaw A be located at the proper distance from the opposing jaw to receive a line of a given measure and be supported in such position so as to sustain the line when the spacers are expanded.

These results are accomplished by the use of a screw D which may be rotated to adjust the jaw and then locked against rotation to locate the jaw in any desired position. The screw D, see Figs. 1 and 2, is arranged longitudinally in the vise frame C parallel with the jaw A and passes thru plain or clearance apertures a in the bearing portions of the block A¹ so that the jaw A may be moved freely in the guideway C¹. At one end, the screw D is attached to a block D¹ which is also mounted in the guideway C¹ but projects slightly beyond the vise frame to abut against the inclined surface e of a vertically reciprocating wedge bar E, the latter being firmly supported facewise in a fixed bracket C² and operated periodically during each machine cycle of operation. For reasons later to appear, the block D¹ is maintained resiliently

in contact with the wedge bar E by a compression spring D² which (as best shown in Fig. 1) surrounds the free end of a rod D³ connected to said block and reacts against a nut C³ mounted in the fixed bracket C². Since the maximum adjustment of the left-hand jaw in standard machines is 30 ems, the screw D in the present instance need only be of a corresponding length; but, in order to effect its rotation from a point convenient to the operator, it is provided at its end opposite that attached to the block D¹ with a shaft extension D⁴ which is journaled in a fixed bracket F at the right of the vise frame C and furnished with a spiral gear D⁵. A rectangular nut D⁶, threaded on the screw and slidably mounted in the guideway C¹ behind the block A¹, presents a square banking surface for the jaw and is intended to sustain it during justification. It is also adapted, by rotation of the screw, to be moved therealong in one direction or the other to adjust the jaw to different predetermined positions. It will be observed, see Fig. 1, that the nut D⁶ serves as a bearing for the screw D, the connection between the block D¹ and the screw being merely a joint to hold these parts together longitudinally while permitting rotation of the screw and the thrust of the jaw to be transmitted directly to the vertical bar E when the line is expanded.

Referring now to the means employed for rotating the screw D and the manner of locking and unlocking the jaw A preparatory to moving it from its adjusted positions, such means, in the present instance, comprise a short shaft G journaled in the bracket F and provided with a spiral gear G¹ meshing with the gear D⁵ above mentioned. The shaft G, altho arranged in a horizontal plane, projects forwardly preferably at an inclination to the shaft extension D⁴ so that a rotatable crank disk G², with which it is provided, will face the operator. The disk G² (see Figs. 1, 4, and 5) is formed with a hub portion G³ pinned to the shaft G and at its outer periphery with a pair of diametrically opposed notches G⁴. An operating handle G⁵, which projects forwardly from the front face of the disk at a point remote from the center, is employed to rotate the disk G² and, thru the shaft G and the spiral gears D⁵, G¹, turn the screw D in one direction or the other as desired. When the nut D⁶, by such operation, has been fed along the screw to a predetermined point, it is merely necessary to lock the disk against rotation to secure the nut so that it may serve in the manner before described. The locking and releasing of the disk G² (as best shown in Figs. 1 and 2) is accomplished by means of a pawl G⁶ pivotally mounted in an upright portion F¹ of the bracket F and arranged in superposed relation to the disk so as to engage one or the other of the notches G⁴ as the disk is rotated. A

light coil spring G⁷, seated in the bracket portion F¹ beneath the rear end of the pawl, urges the front end of the pawl downwardly and serves to maintain it constantly in its engaging position.

70

The foregoing parts and their mode of operation are substantially known to the art and in themselves constitute no part of the present invention, the latter being directed more specifically to a device for indicating the position of the nut D⁶ and the jaw A relatively to the fixed jaw B. This device consists in part of a rotary dial plate H which, in the present embodiment, is operatively connected to the disk G². As best shown in Figs. 4 and 5, the dial plate is in the form of a gear wheel which is loosely mounted on the hub G³ of the disk G² and is arranged flush against the rear face thereof, so that markings on the front face of the dial plate may be clearly read thru suitable apertures G⁸, G⁹ formed in the disk. The two small apertures G⁸ (see Fig. 4) are located diametrically opposite each other and are distinguishable by the relative markings "0" and "6". It is thru the small apertures G⁸ that the setting of the dial is determined; the larger apertures G⁹, on the other hand, altho arranged to expose the greater portion of the dial markings, are merely intended to enable the operator to choose without hesitation the proper direction to rotate the disk in adjusting the jaw A. The figures of the dial herein shown run from 1 to 30 and indicate the adjustment in ems according to the nonpareil pica system of measure.

Meshing with the teeth of the dial plate H is a small pinion H¹ secured to a radially slotted wheel H², which constitutes one element of a Geneva stop-motion device, and which together with the pinion, is loosely mounted on a short fore-and-aft stub shaft H³ supported in an arm F² of the fixed bracket F. The other element of the said Geneva device is in the form of a disk H⁴ secured to the hub of the crank disk G² and provided with an offset arm H⁵ carrying a pin H⁶ to cooperate in the usual manner with the wheel H². By this arrangement, each complete rotation of the crank disk G² will impart a quarter-turn to the pinion H¹, and enable the dial plate H to be moved step by step to different positions as the crank disk is rotated. The relative size of the pinion H¹ and the dial plate H is such that the quarter-turn thus imparted to the former is just enough to bring the next adjacent figure into position where it will be exposed to view thru one or the other of the small apertures G⁸. Consequently, at each complete rotation of the crank disk, a new figure is exposed and the left-hand jaw moved a corresponding distance of one em.

The adjustment of the left-hand jaw according to the foregoing arrangement will 130

now be clear: Assuming the jaw to be set at 16 ems and a change to a longer measure desired, the pawl G^6 is first lifted out of locking engagement with the crank disk G^2 and the latter rotated clockwise until the dial figure selected is brought into vertical alinement with the shaft G and exposed to view thru the small aperture at the top marked "0". If the measure happens to be in half-ems instead of full ems, an extra half-turn is given the crank disk to expose the figure selected thru the small aperture at the bottom marked "6". In this connection, it should be understood that the small apertures referred to, along with the corresponding locking notches G^4 in the crank disk G^2 , might be increased in number (as shown in Fig. 6) in order to provide for the adjustment of the jaw A in ems, points, or other fractions; but for all practical purposes the em and half-em adjustment suffices. When the dial and crank disk have been operated in the manner described, pressure on the locking pawl G^6 is released so that it may automatically snap into the notch G^4 and thus lock the jaw in its newly adjusted position. The adjustment of the jaw from a given measure to a shorter measure merely involves the turning of the crank disk G^2 in the opposite direction. It will be noted (see Fig. 5) that the spiral gear D^5 is splined to the shaft extension D^4 of the screw D so as to permit the latter to be drawn slightly endwise toward the left by the spring D^3 as the wedge bar E is raised to release the block D^1 . This operation takes place after the cast has been made and while the line is still in its adjusted state so as to allow the jaw H to recede slightly and thus release the line preparatory to its elevation from between the jaws. Moreover, the employment of the banking nut D^6 for locating the jaw A in its adjusted positions allows the jaw to be shifted over by hand against the opposing jaw B for the purpose of casting blank slugs. This is an important feature of modern machines which should be preserved, otherwise the block A^1 of the jaw A might be threaded on the screw D . As is well understood, the long finger of the line transfer carriage always restores the left-hand jaw in engagement with the banking nut D^6 prior to each casting operation.

Having thus described my invention, what I claim and desire to secure by Letters Patent of the United States is as follows:

1. In a line casting machine, the combination of a movable line confining jaw, a rotatable screw operatively connected therewith and adapted by its rotation to adjust the jaw to different positions, a crank shaft for rotating the screw, and a device operable directly by said shaft for indicating the adjusted positions of the jaw.

2. In a line casting machine, the combina-

tion of a movable line confining jaw, a rotatable screw operatively connected therewith and adapted by its rotation to adjust the jaw to different positions, and a crank shaft for rotating the screw, said shaft being geared directly to the screw and arranged at an inclination thereto, for the purpose described. 70

3. In a line casting machine, the combination of a movable line confining jaw, a rotatable screw connected thereto and adapted by its rotation to adjust the jaw to different positions, a crank disk for rotating the screw, and a separate rotary dial operable by the disk for indicating the adjusted positions of the jaw. 75

4. In a line casting machine, the combination of a movable line confining jaw, a rotatable screw, a banking nut threaded thereon and adapted by rotation of the screw to adjust the jaw to different positions, a crank disk for rotating the screw, and a separate rotary dial operable by the disk for indicating the adjusted positions of the jaw. 80

5. In a line casting machine, the combination of a movable line confining jaw, a rotatable screw connected thereto and adapted by its rotation to adjust the jaw to different positions, a crank disk for rotating the screw, and a rotary dial operatively connected with the disk so as to turn in synchronism therewith for indicating the adjusted positions of the jaw. 90

6. In a line casting machine, the combination of a movable line confining jaw, a rotatable screw connected thereto and adapted by its rotation to adjust the jaw to different positions, a crank disk for rotating the screw, a rotatable dial for indicating the positions of the jaw as it is adjusted, and means operable by the disk for turning the dial step by step thru a given number of degrees. 100

7. In a line casting machine, the combination of a movable line confining jaw, a rotatable screw connected thereto and adapted by its rotation to adjust the jaw to different positions, a crank disk for rotating the screw, a rotatable dial for indicating the positions of the jaw as it is adjusted, and a Geneva stop-motion device operable by the disk for rotating the dial. 110

8. In a line casting machine, the combination of a movable line confining jaw, a rotatable screw operatively connected therewith and adapted by its rotation to adjust the jaw to different positions, a crank disk for rotating the screw, a rotary dial plate formed with teeth on its outer periphery for indicating the adjusted positions of the jaw, and a rotary pinion operated by the disk for turning the dial. 120

9. In a line casting machine, the combination of a movable line confining jaw, a rotatable screw operatively connected therewith and adapted by its rotation to adjust the jaw to different positions, a crank disk formed 130

with apertures for rotating the screw, and a rotary dial operable by the disk for indicating the adjusted positions of the jaw, said dial being arranged flush against the rear face of the disk so that the markings thereon may be read thru the apertures of the crank disk.

10. In a line casting machine, the combination of a movable line confining jaw, a rotatable screw operatively connected therewith and adapted by its rotation to adjust the jaw to different positions, a crank disk formed

with a pair of diametrically opposed apertures for rotating the screw, and a rotary dial operable by the disk for indicating the adjusted positions of the jaw, said dial being arranged flush against the rear face of the disk so that a selected marking thereon may be read thru one or the other of said apertures, for the purpose described. 15

In testimony whereof, I have affixed my signature hereto. 20

ALFRED W. F. GUEST.
